UNITED STATES PATENT OFFICE.

PETER HENNES, OF MENOMONEE FALLS, WISCONSIN.

CULTIVATOR.

Application filed July 10, 1926. Serial No. 121,554.

This invention relates to cultivators.

Objects of this invention are to provide a novel form of cultivator in which a frame is provided which carries the cultivator blades, and in which manually controlled means are employed to raise and lower the frame to adjust the depth of cut, as required.

Further objects of this invention are to provide a novel adjustment for the cultivator blades so that they may be individually adjusted to vary their angular setting with reference to a vertical axis, and may be adjusted to vary their angular setting with reference to a horizontal axis.

Further objects are to provide a novel form of lifting mechanism for simultaneously lifting both the front and rear ends of the blade carrying frame.

An embodiment of the invention is shown in the accompanying drawings in which:

Figure 1 is a plan view of the cultivator;

Figure 2 is a detailed plan view of one of the blade mountings;

Figure 3 is a longitudinal sectional view on the line 3—3 of Figure 1;

Figure 4 is a side elevation of the structure shown in Figure 2.

Referring to the drawings, it will be seen that the cultivator is provided with an axle 1, whose major portion is square in cross section. The ends of the axle carry the supporting wheels 2 and the intermediate portion or central portion of the axle carries the tongue receiving bracket 3. The tongue 4 is pivotally mounted in the bracket and extends forwardly of the machine.

A main frame 5 is rigidly connected to the axle, and is provided with a plurality of parallel longitudinally extending bars, as indicated at 6. Preferably, a seat 7 is supported by means of a spring arm 8, rigidly attached to the axle.

Beneath the main frame or stationary frame of the machine a movable frame 9 is provided and carries the cultivator blades. This movable frame is of rectangular contour and is provided with longitudinally extending bars, as indicated in Figures 1 and 2. These bars carry a pair of diagonally arranged supporting members 10 which are preferably formed of strap iron, and are provided at their ends and their intermediate points with straight portions 11. These straight portions have plates bolted there-

to. These plates are equipped with a vertically extending part 12 and with a horizontally extending bar 13. The vertical portion 12 of the plates, as may be seen from Figure 4, is attached pivotally adjacent one corner by means of a bolt 14. The opposite end of the vertical portion 12 is provided with a plurality of spaced holes 15 through any one of which the bolt 16 may be passed. The bolt 14, therefore, pivotally holds the plate to the strip member, and the bolt 16 adjustably holds the plate thereto. This plate is provided as stated with a horizontally extending portion 13, as may be seen from Figure 2. This horizontal portion pivotally receives the arm 17 for the cultivator blade 18, the pivotal union being secured by means of the bolt or screw 19 at the opposite end of the plate 13. A plurality of holes 20 are formed through any one of which the bolt or screw 21 may be passed to lock the end of the bar or arm 17 adjustably to the plate. In this manner, the cultivator blade may be rocked about a vertical axis to the desired angular position and also due to the pivotal mounting of the vertical portion 2 of the plate may be rocked about a horizontal axis to secure the angular setting in this direction.

The means for suspending or supporting the frame 9 will be described. This frame is provided on opposite sides with upwardly extending apertured lugs 22 and 23. The rear lug 22 is joined by means of a short link 24 to one arm of a lever 25, such lever being pivoted, as indicated at 26, to the appropriate bar 6 of the stationary frame. The other lug is joined by means of a link 27 to the forward end of a manually manipulated lever 28 which is pivotally mounted at a fixed point, as indicated at 29 in Figure 3. This lever 28 is also connected by means of a link 30 with one end of the lever 25. Thus, when the lever 28 is rocked, the link 27 will be moved and the link 24 will be moved in the same direction due to the link mechanism described above and illustrated particularly in Figure 3. The lever 28 is provided with a locking plunger 31 adapted to enter any of the notches 32 of a locking plate 33 rigidly mounted on the frame of the machine. The plunger 31 may be controlled by the usual hand lever or releasing portion 34.

It is to be noted from reference to Figure

1 that the levers 28 and their associated mechanism are duplicate on opposite sides of the machine. Consequently, both sides of the movable frame of the cultivator and, 5 consequently, all of the cultivator blades may be simultaneously raised or lowered with the utmost facility.

The frame 9 is provided with a pair of U-shaped guides 35 which straddle the 10 squared axle 1, as shown in Figures 1 and 2. The forward end of the movable frame is provided with a U-shaped guide 36 which is equipped with a plurality of apertures 37. This U-shaped guide straddles the tongue 4, 15 as may be seen from Figures 1 and 2. If desired, a pair of bolts or screws 38 may be passed through the apertures 37 on opposite sides of the tongue to hold the guide in a fixed position.

20 It will be seen that a novel form of cultivator has been provided which is so constructed that a movable blade carrying frame may be raised or lowered with the utmost ease. Further, it will be seen that a 25 novel form of mounting for the blades is secured by this invention, whereby the blades may be adjusted angularly either about a vertical or about a horizontal axis.

Although the invention has been described 30 in considerable detail, such description is intended as illustrative rather than limiting as the invention may be variously embodied

and as the scope of such invention is to be determined as claimed.

I claim:

A cultivator comprising a main frame, supporting wheels carried thereby, a movable frame mounted below said main frame, manually controlled levers pivotally mounted on said main frame with said levers located on opposite sides of said main frame, a link extending downwardly from one end of each of said manually controlled levers to said movable frame, an auxiliary lever associated with and positioned below each of said manually controlled levers, said auxiliary lever having one end connected to its corresponding manually controlled lever at a point on the side of the fulcrum of such manually controlled lever opposite from that connected to the said link, and a link extending downwardly from the free end of each of said auxiliary levers to said movable frame, whereby said movable frame may be independently adjusted on either side and whereby each side of the movable frame is retained in a horizontal position lengthwise of the machine in all positions of adjustment.

In testimony that I claim the foregoing 60 I have hereunto set my hand at Milwaukee, in the county of Milwaukee and State of Wisconsin.

PETER HENNES.
